US00D541251S

(12) United States Design Patent (10) Patent No.: US D541,251 S
(45) Date of Patent: * Apr. 24, 2007

(54) PORTABLE PHONE

(75) Inventors: Min-Hyouk Lee, Sunwon-si (KR);
Chang-Hwan Hwang, Goyang-si (KR)

(73) Assignee: Samsung Electronics Co., Ltd.,
Suwon-Si (KR)

() Term: 14 Years

(21) Appl. No.: 29/241,469

(22) Filed: Oct. 28, 2005

(30) Foreign Application Priority Data

Apr. 28, 2005 (KR) 30-2005-0014440

(51) LOC (8) CI. 14-03

(52) U.S. CI. D14/138

(58) Field of Classification Search D14/137,
D14/138, 147, 218, 341-347; 455/90.3, 575.1,
455/575.3, 575.4; 379/433.01-433.13; 361/814;
348/14.02
